A. JOHNSON

SCREW JACK

Filed April 17, 1924

Inventor

A. Johnson,

By Attorney

Patented Feb. 16, 1926.

1,573,611

UNITED STATES PATENT OFFICE.

AUGUST JOHNSON, OF TOIVOLA, MINNESOTA.

SCREW JACK.

Application filed April 17, 1924. Serial No. 707,202.

To all whom it may concern:

Be it known that I, AUGUST JOHNSON, a citizen of the United States, residing at Toivola, in the county of St. Louis and State of Minnesota, have invented certain new and useful Improvements in Screw Jacks; and I do hereby declare the following to be a full, clear, and exact description of the invention, such as will enable others skilled in the art to which it appertains to make and use the same.

This invention relates to lifting jacks, and more particularly to lifting jacks of that type embodying a support, a lower screw having threaded engagement with the support, and an upper screw having threaded engagement with the lower screw.

The invention has for its primary object the provision of a lifting jack of the character stated with means through the medium of which the lower screw may be turned up or locked against downward rotative movement with respect to the support and with means through the medium of which the upper screw may be turned up or locked against downward rotative movement with respect to the lower screw.

A further object of the invention is the provision of a simple, durable and light lifting jack of the character set forth.

With the above and other objects in view, the invention consists in the construction, combination and arrangement of parts hereinafter fully described and claimed, and illustrated in the accompanying drawing, wherein:

Figure 1 is a view in side elevation of a lifting jack constructed in accordance with my invention,

Figure 2 is a sectional view taken on a plane extending vertically and centrally through the lifting jack,

Figure 3 is a detail horizontal sectional view taken on the plane indicated by the line 3-3 of Figure 1, and

Figure 4 is a similar view taken on the plane indicated by the line 4-4 of Figure 1.

The lifting jack comprises a support which consists of a base 1 and a pedestal 2. The support is hollow and angular in cross section. The sides of the pedestal 2 curve inwardly and upwardly and are of increased thickness at their upper ends, as shown at 3, which ends are formed to provide a vertically arranged screw threaded opening 4.

At opposite sides, the pedestal 2 is provided with handles 5.

The opening 4 receives the lower hollow screw 6 which is internally screw threaded adjacent its upper end to receive the upper hollow screw 7.

A screw turning and screw locking member or nut 8 is mounted upon the lower screw 6 for adjustment into contact with a flange 9 at the upper end of this screw or for adjustment into contact with the upper end of the pedestal 2.

When the member or nut 8 is in contact with the flange 9, the lower screw 6 may be turned up with respect to the support through the medium of a lever, not shown, engaged in one of a plurality of openings 10 in the member or nut 8.

When this member or nut 8 is in contact with the upper end of the pedestal 2, the lower screw 6 is locked to the support against any downward rotative movement with respect thereto.

The upper screw 7 is provided with a similar member or nut 11. This member or nut 11 is adapted to be adjusted upon the upper screw 7 into contact with a shoulder 12 at the upper end of the screw or into contact with the upper end of the lower screw 6.

When the nut 11 is in contact with the shoulder 12, the upper screw 7 may be turned up with respect to the lower screw 6 through the medium of a lever inserted in one of a plurality of openings 13 in the nut.

When the nut 11 is in contact with the upper end of the lower screw 6, the upper screw 7 is locked against any downward rotative movement with respect to the lower screw.

The upper end of the upper screw 7 is reduced to provide a journal 14 upon which is rotatably mounted a cap or rest 15. The upper end of the journal 14 is flanged over 95 as shown at 16 to prevent the displacement of the cap or rest 15 which is provided with a load receiving groove 17.

As the support, which comprises the base 1 and pedestal 2, together with the screws 100 6 and 7, are of hollow formation, it should be apparent that the jack is of comparatively light weight. It should be apparent that the screws 6 and 7 may be readily ad-

justed up or down with respect to the support and with respect to each other, and that they may be readily locked against downward rotative movement with respect to the support and with respect to each other. The openings 10 in the member or 105

110

nut 8 are arranged tangentially with respect to the lower screw 6 and the openings 13 in the member or nut 11 have a diametrical arrangement with respect to the upper screw 7. To permit the lower screw to be held against rotation while adjusting the member or nut 8 thereon, the flange 9 thereof is of polygonal outline to permit it to be engaged by a wrench.

10. What is claimed is:—

A screw jack comprising a support, a lower screw having threaded engagement with the support and provided at its upper end with a polygonal shoulder, a member 15 provided with a plurality of openings and threadedly mounted upon said screw for adjustment into contact with said support to lock the screw against downward rotative movement with respect to the support and 20 for adjustment into contact with said

shoulder to permit the screw to be turned outwardly with respect to the support, an upper screw having threaded engagement with the lower screw and provided at its upper end with a shoulder, a member provided 25 with a plurality of openings and threadedly mounted upon the upper screw for adjustment into contact with the upper end of the lower screw to lock the upper screw against downward rotative movement with respect 30 to the lower screw and for adjustment into contact with the shoulder at the upper end of the upper screw to permit said upper screw to be adjusted upwardly with respect to the lower screw, and a cap or rest carried 35 by the upper screw.

In testimony whereof I affix my signature.

AUGUST JOHNSON.
